UNITED STATES PATENT OFFICE.

MAURICE O. SMITH, OF ST. LOUIS, MISSOURI.

DESIGN FOR A VAPORIZER FOR GAS-ENGINES.

57,282.

Specification for Design.

Patented Mar. 8, 1921.

Application filed April 24, 1920. Serial No. 376,421. Term of patent 14 years.

To all whom it may concern:

Be it known that I, MAURICE O. SMITH, a citizen of the United States of America, residing in St. Louis, in the State of Missouri, have invented a new, original, and ornamental Design for a Vaporizer for Gas-Engines, of which the following is a specification, reference being had to the accompanying drawing, forming a part thereof, in which—

Figure 1 is a front side elevation of the vaporizer embodying my invention;
Fig. 2 is a top plan view; and
Fig. 3 is a rear end elevation.

I claim:

The ornamental design for a vaporizer for gas engines, as shown.

In testimony whereof, I have signed my name to this specification.

MAURICE O. SMITH.
